(71) Applicant: **Otis Elevator Company**, Farmington, CT (US)

(72) Inventor: **Sarah Rose Andrew**, Portland, OR (US)

(73) Assignee: **OTIS ELEVATOR COMPANY**, Farmington, CT (US)

(**) Term: **15 Years**

(21) Appl. No.: **29/599,200**

(22) Filed: **Mar. 31, 2017**

(51) LOC (11) Cl. **14-04**

(52) U.S. Cl.

USPC **D14/486**; D14/492

(58) **Field of Classification Search**

USPC D14/485-495

CPC G06F 3/04817; H04N 1/00424

(74) *Attorney, Agent, or Firm* — Cantor Colburn LLP

(57) **CLAIM**

The ornamental design for a display screen or portion thereof with graphical user interface, as shown and described.

DESCRIPTION

FIG. 1 is a front view of a display screen or portion thereof with graphical user interface showing my new design in accordance with a first embodiment; and,

FIG. 2 is a front view of a display screen or portion thereof with graphical user interface showing my new design in accordance with a second embodiment.

The broken lines showing the display screen or portion thereof and portions of the graphical user interface form no part of the claimed design.

1 Claim, 2 Drawing Sheets
